UNITED STATES PATENT OFFICE

162,272

COMBINED PLANT RECEPTACLE AND
SUPPORT

Bernard Yellin, Chicago, Ill.

Application January 12, 1950, Serial No. 7,173

Term of patent 7 years

(Cl. D35—3)

To all whom it may concern:

Be it known that I, Bernard Yellin, a citizen of the United States and resident of Chicago, in the county of Cook and State of Illinois, have invented a new, original, and ornamental Design for a Combined Plant Receptacle and Support, of which the following is a specification, reference being had to the accompanying drawing, forming a part thereof.

Fig. 1 is a side elevational view of a combined plant receptacle and support, showing my new design, a portion being broken away to show details thereof.

Fig. 2 is a top plan view of the same, albeit on a reduced scale.

The side opposite to that shown in Fig. 1 is substantially identical in configuration to the illustrated side.

I claim:

The ornamental design for a combined plant receptacle and support, substantially as shown and described.

BERNARD YELLIN.
